United States Patent Office.

HARVEY BOSWORTH, OF CHAMPLAIN, NEW YORK.

Letters Patent No. 103,133, dated May 17, 1870.

IMPROVED CLOTHES-DRIER.

The Schedule referred to in these Letters Patent and making part of the same.

To all whom it may concern:

Be it known that I, HARVEY BOSWORTH, of Champlain, in the county of Clinton and in the State of New York, have invented certain new and useful Improvements in Clothes-Racks; and do hereby declare that the following is a full, clear, and exact description thereof, reference being had to the accompanying drawing and to the letters of reference marked thereon, in which drawing—

Figure 1 is a front elevation of one of the modifications of my device;

Figure 2 is a front elevation of another modification of the same; and

Figure 3 is a side elevation of each modification of the same.

Letters of like kind denote like parts in each figure.

The object of this invention relates to the construction of a clothes-rack for convenient use in a house, so arranged that it may be pivoted at its bottom to the wall of a room, and inclined for use at any desirable angle and there secured, or may be folded closely against the wall out of the way, and there kept in place; and consists in the peculiar construction of the clothes-rack, the manner in which it is secured to the wall of a room, and in the method of adjusting and securing it at any desirable distance from said wall.

In the drawing—

A and B represent two modifications of the clothes-rack, and

C, the wall to which they are attached.

A is a rack made in the usual form, with two side pieces, *a*, arranged parallel to each other at any desired distance apart, and

b are rounds, arranged parallel to each other, connecting the side pieces and passing through them, of which rounds as many may be used as required by the size of the rack.

These rounds project a little beyond the side pieces on one side, and are there furnished with heads *c*, having a grooved neck.

The bottom of each side piece has also a hook, *d*,

pivoted into a staple driven into the wall of the room at any convenient point.

Another staple, *e*, is driven into the wall at a point opposite the top center of the rack, as it would be when pivoted and pressed against the wall.

A cord, *f*, attached to the staple *e*, passes through an eye, *g*, attached to the under center of the top round, and thence along under said round out through the side piece which has the heads *c* upon it, and terminates in a ring, *h*. The object of said cord is to draw said rack up closely to said wall, or to allow it to drop away from said wall any desired distance, and in either case to secure it in position by placing the ring *h* over one of the heads *c*.

The rack B differs from the rack A, in having top and bottom pieces as well as side pieces all framed together, and, instead of rounds, having a cord, *k*, passed through the sides, and from side to side across in parallel lines, as closely as desired.

It also differs in the haul-up cord *f*, in having a hook at its end instead of a ring, by the use of which hook, passed over any one of the cords *k*, this rack is held in position.

The advantages of my rack consist in cheapness of first cost, in simplicity of construction, and in its great convenience, being always at hand and ready for use, and never in the way.

Having thus fully set forth the object, nature, and merits of my invention,

What I claim as new, and desire to secure by Letters Patent, is—

The hereinbefore-described clothes-rack A, consisting of the side pieces *a*, connected together by means of the rounds *b*, the cord *f*, the ring *h*, and the heads *c*, all constructed and arranged substantially as and for the purpose shown.

In testimony that I claim the foregoing, I have hereunto set my hand this 26th day of March, 1869.

HARVEY BOSWORTH.

Witnesses:

ROYAL CORBIN,

WILLIAM BOSWORTH.
